(57) **CLAIM**

The ornamental design for a housing of exercise machine, as shown and described.

DESCRIPTION

FIG. 1 shows a perspective view of the present design. FIG. 2 shows a right elevational view of the present design. FIG. 3 shows a top plan view of the present design. FIG. 4 shows a front elevational view of the present design. FIG. 5 shows a bottom plan view of the present design. FIG. 6 shows a left elevational view of the present design. FIG. 7 shows a rear elevational view of the present design. FIG. 8 shows a perspective view of the present design of a housing of exercise machine in its environment of use in an exercise machine shown in broken line illustration; and, FIG. 9 shows another environmental perspective view thereof.

The broken line illustration in the drawing disclosure is for illustrative purposes only and forms no part of the claimed design.
